CLAIM

The ornamental design for a portion of a display screen having a computer-generated graphical user interface for reviewing adjustments made to inventory items, as shown and described.

DESCRIPTION

The FIGURE is a front view of a portion of a display screen having a computer-generated graphical user interface for reviewing adjustments made to inventory items.

The broken lines showing the portion of the display screen form no part of the claimed design. The remaining broken lines showing portions of the computer-generated graphical user interface form no part of the claimed design.
